UNITED STATES PATENT OFFICE.

OTTO REINHARDT, OF CENTRAL FALLS, RHODE ISLAND.

SHADE AND CURTAIN-ROD HOLDER.

Application filed December 10, 1926. Serial No. 153,830.

This invention relates to certain new and useful improvements in shade and curtain rod holders and the primary object of the same is to provide a more simplified and economical holder and one which involves a minimum of parts compactly assembled and of strong and durable form.

Still further the invention aims to provide a holder which is readily adaptable 10 for use in bay or corner windows.

In the drawings:—

Figure 1 is a perspective view of the invention, partly broken away to show the construction, and

15 Figure 2 is a like view showing the device in use with the corner of bay windows.

In proceeding in accordance with the present invention, a base member is employed which consists of a metal plate 1 having its 20 side edges curled or rolled to provide wings 2, the plate being secured to the window frame by fasteners 3. The shade holder is formed of a resilient rod doubled upon itself to form an eye 4 to receive the shade pintle 25 P and has its ends bent to provide horizontal arms 5, the latter being offset and formed with fingers 6 that extend at right angles to the arms. The fingers 6 engage within the wings 2, and are of a substantial 30 length to receive firm support therefrom, and also due to the resilient nature of the rod, same are sprung into engagement with the wings 2. The holders accordingly are afforded a firm support and still can be 35 easily and quickly slid along the length of the base to adjust the same.

The supports for the curtain rod 7 are formed of resilient rods doubled upon themselves at 8 and having divergent arms 9, the 40 ends 10 of which are bent downwardly and passed through registering perforations 11 provided therefor in the wings 2 whereby the curtain holder receives support from each of the wings 2 as is also true in the instance of the shade holder. A plate 12 seats upon the doubled parts 8 of the rods and has depending ears 13 perforated to receive the doubled parts 8. Posts 14 are secured to the plate and are received in sockets 15 50 of the fittings which latter carry the curtain rods 7.

In adapting the invention for use at the corners of bay or corner or other windows meeting at an angle, the base plates and the 55 curtain rod holders are of the same structure as above described. The resilient rod

with its doubled part 8, arms 9 and fingers 10, also are of the same construction, but in this form of the invention two base plates 1 are employed and the fingers 10 are inserted through the adjacent perforations 11 of the two base plates, so that but one curtain holder is necessary for the two base plates, or otherwise stated such one holder is common to each of the two base plates. 60 In this form of the invention, however, a plate 20 of the greater width is employed and which has perforated ears 21 secured to the doubled part 8 of the rod as described in connection with Figure 1. The increased 65 width of the plate is to accommodate four posts 21 for support of as many curtain rods. Fig. 2 illustrates but two rods, one of flat and the other of round form, but this feature has nothing to do with the 75 present invention.

From the foregoing, it will be seen that two base plates and two shade holders and but one curtain holder is necessary at the angle of adjacent windows, thus providing 80 fewer parts and a more compact assembly.

It is also to be noted that the wings serve not only to support the shade holder but the curtain holder as well.

Having thus described my invention what 85 I claim as new and desire to secure by Letters Patent is—

1. In combination with supporting means having spaced perforated wings, a curtain holder composed of a rod doubled upon 90 itself and having its ends diverged to provide arms and having the latter bent downwardly to form fingers engaged in the perforation of each of the wings and a plate having a post thereon and having depending ears perforated to receive the doubled part of the rod.

2. In combination with supporting means having spaced perforated wings, a curtain holder composed of a rod doubled upon 100 itself and having its ends diverged to provide arms and having the latter bent downwardly to form fingers engaged in the perforation of each of the wings, a post, and means to connect the post to the doubled 105 part of the rod.

3. In combination with a pair of base plates having spaced perforated wings and formed for attachment to angularly related window frames, a curtain holder composed 110 of a rod doubled upon itself and having divergent arms formed with depending fin-

- gers for engagement in the perforations of the wings of each of the plates, a plate superposed on the doubled part of the rod and having depending ears perforated to receive 5 the doubled part, and posts on the plate.
4. In combination with a pair of base plates having spaced perforated wings and formed for attachment to angularly related window frames, a curtain holder composed 10 of a rod doubled upon itself and having divergent arms formed with depending fingers for engagement in the perforations of the wings of each of the plates, posts, and means to secure the posts to the doubled 15 part of the rod.
5. In combination with a pair of spaced independent base members formed for attachment to angularly related window frames a curtain holder common to each of 20 the members, and means to secure the holder to each of the members including spaced arms engaged with each of the base members.
6. In combination with a pair of base 25 members formed for attachment to angularly related window frames, a curtain holder common to each of the members having divergent arms and depending fingers, and means on the members to receive the fingers.
- 30 7. In combination with a pair of base members formed for attachment to angularly related window frames a curtain holder common to each of the members having divergent arms and depending fingers, and upper and lower wings on the members perforated to receive the fingers so as to support each of the latter from two points. 35
8. In combination with a base plate having inwardly extending spaced and perforated wings, a shade holder having arms 40 formed with resilient fingers slidably engaged within the wings, and a curtain holder having a pair of arms provided with vertical fingers disposed in front of the base plate and engaged through the perforations 45 of each of the wings whereby the latter support both holders.
9. In combination with a base plate having spaced opposed inwardly extending wings, a shade holder having arms provided 50 with expandible horizontal fingers sprung into the wings and slidably supported thereby, said fingers being of a length whereby same are afforded bearings in the wings so as to support the holder from the 55 wings.
10. In combination with supporting means having opposed wings each provided with a pair of registering perforations, a curtain holder having divergent arms each 60 of which arms has a depending finger, said fingers being engaged through the registering perforations of the wings so as to be supported by each of the wings.
- In testimony whereof I have hereunto 65 signed my name to this specification.

OTTO REINHARDT.
